Samuel H. Ransom, of Albany, N.Y.
Letters Patent No. 1799 - Dated July 7th 1863.

The schedule referred to in these Letters Patent and making part of the same:

To whom it may concern:

Be it known that I, Samuel H. Ransom, of the City and County of Albany, and State of New York, have produced a new and original design for the Plates of a Cook Stove, which stove is named the "Home Guard"; and I declare that the annexed delineations are full and accurate representations of the ornamental design on the different plates; those plates not shown are of the same design as those annexed.

A represents the side of the stove, with the oven doors in.
B " the back of the stove.
C " the front of the stove, without doors.
D " one of the front doors.

These with other plates similarly ornamented, when mounted together forming the cook stove called the "Home Guard".

What I claim as my production, and desire to secure by Letters Patent, is, the combination and arrangement of ornamental figures and forms represented in the accompanying Photographs, forming together the ornamental design for a cook Stove.
